FISH LURES

Ewell J. Harris, Rte. 3, Box 35-A,
Adrian, Mich. 49221

Filed June 9, 1970, Ser. No. 23,404

Term of patent 14 years

Int. Cl. D22—05

U.S. Cl. D22—27

FIG. 1 is a side elevational view of a fish lure showing my new design; and

FIG. 2 is a plan view of the fish lure shown in FIG. 1. The broken line showing is for illustrative purposes only.

I claim:

The ornamental design for fish lures, substantially as shown and described.
